F. C. WHITEHOUSE

WEATHER STRIP

Filed June 9, 1924

Fig. 5.

Attorneys

UNITED STATES PATENT OFFICE.

FRED C. WHITEHOUSE, OF OAK PARK, ILLINOIS.

WEATHER STRIP.

Application filed June 9, 1924. Serial No. 718,950.

To all whom it may concern:

Be it known that I, FRED C. WHITEHOUSE, a citizen of the United States, residing at Oak Park, in the county of Cook and State 5 of Illinois, have invented new and useful Improvements in Weather Strips, of which the following is a specification.

This invention relates to weather strips especially adapted for use on doors and 10 windows.

An important object of the invention is to provide a weather strip which may be applied to the standard sash without marring the appearance of the same and without interfering with the freedom of movement of 15 the sash.

A further object is to provide a weather strip which will positively exclude dust and air.

20 A further and equally important object of the invention is to provide a weather strip which may be applied without the exercise of unusual skill and which is so constructed that a constant and air tight connection is maintained between the parts.

Also, an important aim of the invention is to provide a weather strip having means whereby to permit of a limited lateral movement of the sash.

30 Other objects and advantages will be apparent during the course of the following description.

In the accompanying drawing forming a part of this application and in which like 35 numerals are employed to designate like parts throughout the same,

Figure 1 is a perspective of the improved weather strip applied;

Fig. 2 is a group perspective of the 40 weather strip;

Fig. 3 is a horizontal sectional view through the weather strip, the female member of the same being shown in the position it occupies immediately prior to being attached to the window frame;

Fig. 4 is a horizontal sectional view taken on line 4—4 of Fig. 1, and

Fig. 5 is a detail transverse sectional view 50 illustrating the means to establish an air tight connection between the upper and lower sashes.

In the drawing, wherein for the purpose of illustration is shown a preferred embodiment of the invention, the numeral 5 designates a window frame having spaced parallel jamb strips 6 between which the stiles

of a sash 7 are slidable. It might be said that the spaced parallel jamb strips 6 define pairs of grooves within which the edge portions of the sash are slidable. 60

The invention forming the subject matter of this application resides in the provision of simple and reliable means whereby a dust and air tight connection is established between the sash and the frame and to this 65 end certain of the jamb strips 6 are provided with angle-shaped metallic strips 8. Figs. 1 and 2 illustrate that each angle strip 8 is provided with an attaching flange 9 having spaced openings 10 for the reception of 70 small nails or other suitable fastening devices. The flanges 9 are secured flatly in contact with the jamb strips 6 and the flanges 11 of the angle strips 8 extend inwardly into overlapping relation with the 75 stiles of the several sashes.

One edge portion of each flange 11 is rolled to provide a rounded bead 12, which as plainly illustrated in Figs. 3 and 4, is received between the co-acting sides 14 and 16 80 of a sash carried strip generally designated by the numeral 18. The sash carried strip 18 is formed from a single length of rather stout metal bent longitudinally between its longitudinal edges to provide the opposed sides 14 and 16 and the edge portions of the opposed sides 14 and 16 are bent outwardly and then inwardly to define a channel 20 to slidably receive the bead 12. The return bends at the edges of the opposed 85 sides 14 and 16 define contacting beads 21 which flatly bear against opposite sides of the flange 11 and, therefore, cooperate with the same in establishing an air tight joint. Also, the opposite sides of the bead 12 contact with the opposed sides of the bead receiving channel 20 so that an effective four-point contact is provided between the two sections of the weather strip. 90

Attention is especially directed to the fact 100 that the spring sides 14 and 16 normally have a slight space between them and when the section 18 of the weather strip is tacked or otherwise secured to the stile of the sash this space is taken up and the edge portions 105 of the sides 14 and 16 are more firmly pressed into engagement with the bead 12 and the opposite sides of the flange 11 so that a constant tension is exerted. It is thus seen that the fastening means 25 of 110 the female member 18 not only connect the female member to the sash but also pro-

vide a reliable means for maintaining a constant spring tension between the parts.

A weather strip constructed in accordance with this invention may be applied either to the inner, outer or the intermediate jamb strips without interfering with the freedom of movement of the upper and lower sashes and without in any way marring the appearance of the same.

Also, a weather strip constructed in accordance with this invention may be conveniently applied by an unskilled person by merely tacking the several sections in the proper place. A limited lateral sliding movement of each sash may take place without permanently distorting the weather strip. However, the improved weather strip reduces this lateral sliding movement to a minimum and also brings about a corresponding reduction in the noise caused by the lateral sliding movement of the sash.

In carrying out the invention the weather strips for the lower sash preferably terminate at the top of the lower sash. Also, the weather strips for the upper sash terminate at the bottom of the upper sash.

Fig. 5 illustrates that the top of the lower sash may be provided with an air and dust excluding strip 30 which has one edge portion offset and overhanging a second strip 32 secured to the lower rail of the upper sash. This connection between the rails of the upper and lower sashes provides an absolutely air, dust, cinder and smoke tight connection between the sashes and, therefore, provides an effective means for sealing the windows.

The invention forming the subject matter of this application can also be used in connection with doors.

It will be seen that the novel weather strip is simple to install, and requires no grooving or cutting of the sash for that purpose. Once the outfit is installed, the four-point contact referred to seals the sash in the manner described, and no further attention to the installation is required.

Having thus described the invention, what is claimed is:

1. A sealing means for windows comprising an angle strip having right angle flanges, one of which is provided with attaching means and the other having its edge portion formed with a longitudinally extending bead, and a female strip having normally spaced spring sides, the edge portions of which are formed with inwardly directed bends defining beads contacting with the beaded flange of the angle strip between the bead thereon and the inner edge of the flange, the bead on said flange contacting

with both of the sides of said female member whereby to cooperate with the beads on the edges of said sides to provide a four-point contact between the angle strip and the female member.

2. A sealing means for windows comprising an angle strip having right angle flanges, one of which is provided with attaching means and the other having its edge portion formed with a longitudinally extending bead, a female strip having normally spaced spring sides, the edge portions of which are formed with inwardly directed bends defining beads contacting with the beaded flange of the angle strip between the bead thereon and the inner edge of the flange, the bead on said flange contacting with both of the sides of said female member whereby to cooperate with the beads on the edges of said sides to provide a four-point contact between the angle strip and the female member, and a fastening device extending through the spring sides of said female member to draw the spring sides together to secure the female member to an object.

3. A sealing means for windows comprising a strip having one edge portion formed with a return bend defining a bead, a second strip having normally spaced spring sides, the edges of which are formed with inwardly extending bends defining beads contacting with the opposite sides of said strip at a point spaced from said first-named bead, the bead of said strip contacting with the spring sides at a point spaced from said second-named beads whereby a four-point contact is provided between the first and second-named strips.

4. A sealing means for windows comprising a strip having one edge portion formed with a return bend defining a bead, a second strip having normally spaced spring sides, the edges of which are formed with inwardly extending bends defining beads contacting with the opposite sides of said strip at a point spaced from said first-named bead, the bead of said strip contacting with the spring sides at a point spaced from said second-named beads whereby a four-point contact is provided between the first and second-named strips, and an attaching device extending through said spring sides and drawing the same together whereby a constant tension is exerted on said first-named strip by said second-named beads.

In testimony whereof I affix my signature.

FRED C. WHITEHOUSE.
